UNITED STATES PATENT OFFICE.

EMIL C. MUELLER, JR., OF ELIZABETH, NEW JERSEY, ASSIGNOR TO WESTERN ELECTRIC COMPANY, INCORPORATED, OF NEW YORK, N. Y., A CORPORATION OF NEW YORK.

TELEPHONE-TRANSMITTER MOUTHPIECE.

1,252,475.

Specification of Letters Patent. Patented Jan. 8, 1918.

Application filed February 26, 1917. Serial No. 151,009.

To all whom it may concern:

Be it known that I, EMIL C. MUELLER, Jr., a citizen of the United States, residing at Elizabeth, in the county of Union and State 5 of New Jersey, have invented certain new and useful Improvements in Telephone-Transmitter Mouthpieces, of which the following is a full, clear, concise, and exact description.

10 This invention relates to telephone transmitter mouth-pieces, and the method of making them, and has for its object a mouth-piece which may be easily cleaned, and one which will present a good appearance and 15 be more durable and more easily manufactured than those in common use at the present time.

The telephone mouth-pieces of hard rubber or similar compounds, which have been 20 in common use heretofore are objectionable because they soften and lose their shape when placed in hot water to be cleaned, and also because they are easily broken or chipped in 25 service. Those made of porcelain or a similar substance which are screwed directly into the face plate of the telephone transmitter or into an adapter which is screwed or otherwise fastened to the transmitter face, have failed to meet service re-

30 quirements satisfactorily, since the threads are difficult to mold with accuracy, and are easily broken or chipped, the broken parts therefrom often wedging against the transmitter diaphragm and interfering with the 35 operation of the transmitter. Moreover, mouth-pieces in which a body portion of porcelain or similar material is held to the transmitter face plate by a screw threaded metal ferrule or adapter, to which the por- 40 celain is cemented, have been found to be unsatisfactory not only because of the cost of providing a suitable construction, but also because of the difficulty of procuring a cement which will not dissolve or lose its 45 adhesive properties in boiling water. Moreover, difficulty has been experienced in obtaining a cement which does not harden to such an extent that the structure is substantially rigid, resulting in a high percentage 50 of chipped or broken mouth-pieces under ordinary service conditions.

In order to eliminate the above objections, this invention provides a telephone mouth-piece having a body member of porcelain or 55 similar substance secured to an adapter or

ferrule, one end of which is threaded to screw into the front plate of a transmitter. The porcelain member is secured to the ferrule by means of a resilient adhesive binder, and the parts are so constructed as to provide a maximum space between the porcelain and the ferrule for the binder, thereby making the structure less rigid and reducing the danger of breakage to a minimum. More specifically this invention provides a 65 mouth-piece in which a metal ferrule is provided with inwardly extending lugs adapted to engage external projections or threads in the body member of porcelain or similar substance, the parts then being held in locked 70 engagement by means of vulcanized rubber. The use of a ferrule having inwardly extending lugs is much to be preferred over the use of a ferrule inwardly threaded, not only because of the lower cost of manufacture, 75 but also because of the better anchorage obtainable for the binder, and the greater amount of this resilient material available to take up shocks and prevent breakage.

The several features of this invention may 80 be more readily understood by referring to the accompanying drawings, in which Figure 1 shows the assembled structure partly in section; Fig. 2 shows the construction of the porcelain body member; and Fig. 3 85 90 shows the metal ferrule, by means of which the mouth-piece is fastened to the transmitter face plate.

The body portion 5, of the usual funnel shape, and preferably of porcelain, is provided at its base with a contracted portion 6, which in turn is provided with external threads 7, as clearly shown in Fig. 2. The adapter or ferrule 8 comprises a metal ring having an enlarged portion 9, and a contracted portion 10. The contracted portion is outwardly threaded to fit into the face plate of a telephone transmitter (not shown). The enlarged portion 9 is provided with indentations 11 projecting inwardly, and adapted to engage the threads of the porcelain body member. The inner surface of the enlarged portion 9 is roughened by some method, such as knurling, to increase the adhesion between such surface and the 100 binder 12. As a further aid in securing this binder to the porcelain body member, one or more short sections of the thread are removed, leaving spaces 13 into which the binder extends and locks the parts together. 105 110

The binder 12, which secures the body portion 5 and the ferrule 8 together, is preferably applied to the contracted portion of the porcelain in the form of a paste or liquid of 5 rubber compound. The ferrule is then pressed into place by imparting a relative rotary motion between the ferrule and the porcelain body member, causing the projections or lugs in the ferrule to engage the 10 threads of the porcelain member and draw the two parts together. The assembled structure is then placed in an oven and kept at a temperature of approximately 170 degrees centigrade for one or two hours to vul- 15 canize the rubber. This process forms a resilient adhesive binder, securely fastening the porcelain member and ferrule together. The structure is very easily assembled and may be very easily cleaned in boiling water 20 without loosening the parts. The inwardly extending lugs in the ferrule provide a means for fastening the parts together which is cheap to manufacture and one which does not mar the appearance of the 25 completed structure. Moreover, the resiliency of the rubber after vulcanization is sufficient to allow it to absorb shocks resulting from rough usage of the mouth-piece, with a minimum danger of breakage.

30 What is claimed is:

1. A telephone transmitter mouth-piece comprising a body member having external threads at one end, a ferrule having internal projections engaging said external threads, 35 and a binder holding the body portion and ferrule together.

2. A telephone transmitter mouth-piece comprising a body member having external threads at one end, a ferrule having internal 40 projections engaging said external threads, and a resilient adhesive binder holding the body portion and ferrule together.

3. A telephone transmitter mouth-piece comprising a body member having external 45 projections at one end, a ferrule having in-

ternal projections engaging said external threads, and a resilient adhesive binder holding the body portion and ferrule together.

4. A telephone transmitter mouth-piece 50 comprising a body member having external threads at its one end, an attaching ferrule provided with projections extending inwardly and adapted to engage said threads, and a resilient adhesive binder for securing 55 said body member and said ferrule together.

5. A telephone transmitter mouth-piece, comprising a porcelain body member provided at one end with external threads, a ferrule for attaching said body member to a 60 transmitter, said ferrule being provided with projections extending inwardly to engage said threads, and an adhesive resilient binder for securing said body member and said ferrule together.

6. A telephone transmitter mouth-piece, comprising a body member having a contracted portion provided with external threads, a ferrule for attaching said body member to a transmitter, said ferrule being 70 provided with projections adapted to engage said threads, and a resilient adhesive binder between said body member and said ferrule.

7. A telephone transmitter mouth-piece, 75 comprising a body member having a contracted portion provided with external threads which are interrupted at one or more places, a ferrule for attaching said body member to a transmitter, said ferrule 80 being provided with projections adapted to engage said threads, and a resilient adhesive binder between said body member and said ferrule, said binder being anchored at the interrupted portions of said threads.

In witness whereof, I hereunto subscribe my name this 24th day of February, A. D., 85 1917.

EMIL C. MUELLER, JR.
